CLAIM

The ornamental design for a corinthian column on pedestal shaped bottle, as shown and described.

DESCRIPTION

FIG. 1 is a front elevational view of a bottle showing our new design (the rear elevational view is a mirror image). FIG. 2 is a side elevational view therof (left and right side are the same).

FIG. 3 is a top view thereof;

FIG. 4 is a cross-section view taken along line 4-4 of FIG. 1, the shaft is shown separately for clarity of illustration; and,

FIG. 5 is a cross-section view taken along line 5-5 of FIG. 1.

The bottom of the bottle is unornamented.
